UNITED STATES PATENT OFFICE.

ALFRED WEBER, OF NEW YORK, N. Y.

DESIGN FOR AN INCANDESCENT-LAMP BULB OR SIMILAR ARTICLE.

Application filed August 12, 1927. Serial No. 23,068. Term of patent 3½ years.

To all whom it may concern:

Be it known that I, ALFRED WEBER, a citizen of Austria, residing at New York, in the county of New York and State of New York, have invented a new, original, and ornamental Design for an Incandescent-Lamp Bulb or Similar Article, of which the following is a specification, reference being had to the accompanying drawing, forming part thereof.

The figure is a side elevational view of the incandescent lamp bulb, showing my new design.

I claim:

The ornamental design for an incandescent-lamp bulb or similar article, as shown.

ALFRED WEBER.
